UNITED STATES PATENT OFFICE.

FLORENCE ROSENA WALKER, OF MARCELLUS, NEW YORK.

TOY OR DOLL HOUSE CONSTRUCTION.

Application filed November 3, 1926. Serial No. 146,060.

The invention has for an object to present a toy or doll house in such manner as to enhance the development of the home-building instinct and enable the teaching 5 of practical ideas in the construction of structures of this character which will be useful in inducing technical activities and cultivate the ability to comprehend such constructions. It is, however, differentiated 10 from practical construction which might be followed in full sized dwellings in a novel way to adapt it to the activity of a child and enable the ready building of a house with a good flat foundation or bottom sur- 15 face throughout.

A further important object of the invention is to provide a novel form of toy house construction tending to facilitate the use thereof and improve its adaptability to ac- 20 tivities of children in playing therewith.

Additional objects, advantages and fea- 25 tures of invention reside in the construction, arrangement and combination of parts, as will be readily understood from the following description and accompanying drawings, wherein

Figure 1 is a front elevational view of a house constructed in accordance with my invention.

Figure 2 is a rear view of the house with a portion of one end omitted.

Figure 3 is a view looking into the house when open for access.

Figure 4 is an end elevation of the house.

Figure 5 is a top view with a portion broken away to show the interior construction.

Figure 6 is a detail of one of the constructions in the wall units.

Figure 7 is a fragmentary plan of the floor.

Figure 8 is a cross section of the floor.

Figure 9 is a vertical edge view of the wall 12 of Figure 6.

There is illustrated a house constructed in two sections 10 and 11 hingedly connected, the section 10 comprising a front wall 12 having a door 13 therein, a back wall 14, an end 15, and roof sections 16 and 17 at 50 the rear and front respectively, all mounted on a base floor 18 suitably framed. The section 11 is similarly constructed, with the exception that the front portion has no door therein. Windows 19 are shown in the end 55 above mentioned and may be variously located as desired. The house sections 10 and

11 are open at the inner or abutting sides, where a suitable framing 20 is provided to stiffen them, as at 20 in Figure 3. The floor of each section comprises a suitable number 60 of foundation sills or bottom stringers 21, upon two of which joists 22 are laid running lengthwise of the complete house, and on these in turn the face or top floor proper 65 is laid, consisting of miniature planks ex- tending from the front edge of the flooring to the back edge. The floor is sufficiently smaller than the external measurement of the house to permit face boards 23 to be se- 70 cured to the end edges as shown in Figures 1, 2 and 4, in proper relation with the major facing material of the walls. The front 12 of each section is built up after the manner shown in Figure 6, as well as the back 14 and end 15 which is modified as necessary 75 to fit the roof, and as may be required by the introduction of doors or windows. The wall sections as shown in Figure 6 comprise upper and lower plate and sill 24' which are mortised at the ends to receive projections 80 such as shown in Figure 3 from cross members in the house framing 20 in the middle and on the end 15. Studs 26 of suit- 85 able number are set between the plate and sill and clap-boards 27 then nailed thereon, the ends of the boards stopping short of the ends of the plate and sill, so that panel or corner boards 28 may be butted against the ends of the clap-boards and secured to the plate and sill and to the floor 18 there- 90 below, as shown in Figures 1 and 3. The ends 15 are formed with a gable extension 15' fitting the roof and may be constructed by the use of a frame such as shown at 20 95 in Figure 3, with discretionary structure at the upper part, faced with clap-boarding as shown. The roof sections 16 and 17 com- 100 prise longitudinal girders 29, and rafters 30, with a suitable roof covering 31, which may simulate shingles or other familiar form of roofing.

It is to be noted that the front roof section 17 is wider than the rear section 16, so that it projects at the front of the house, forming an eave 32, but the section 16 stops flush with the rear face of the house, so that there is no eave at the rear, as may be seen in Figures 2 to 5, inclusive. The roof sections both project over the end 15 to form eaves. The two end sections of the house abut con- 110 tinuously and snugly in a plane at right angles to the longitudinal axis of the build-

ing, and the floor 18, frame 20 and parts 14 and 15 are brought snugly to this plane. A ceiling 33 and interior wall facing 34 may be provided within the building, if desired, 5 as will be explained.

In the production of the parts for this building, the plates, sills, stringers, and girders are suitably mortised to receive the members which are to be secured transversely thereto, for the guidance of children in assembling the parts. All of the pieces in proper form are supplied knock-down, so that the house may be constructed from the lumber, using brads or small nails to secure 15 the parts together, and a complete building operation carried through by a child, in such a manner as to train the mind of the child in comprehending problems of this character.

20 In the construction of the house, the floor is first built complete, and the front, back, end and roof sections assembled separately, the front, back and ends being set up on the outer edge portions of the floor and secured 25 thereto and to each other, the frame 20 in addition being set upon the inner edges of the floor and secured to the front and back sections. The wall facing board 34 may then be set within the walls and secured, after 30 which the ceiling 33 may be put in place on each section, which may consist of wall board or other thin material in one piece for each ceiling. The roof sections 16 and 17 are then 35 adjusted in place and secured to the respective supporting parts, and to each other.

The two sections are then adjusted with the backs together and their open ends in the same direction and hinges 35 secured thereto so that they may swing together into snug abutment to form a complete house as shown 40 in Figure 1. The omission of the eaves at the back of the house is important to permit the opening of the structure fully for placing of furniture, dolls or the like within the house, as well as permitting the full opening 45 of the house to bring the back sides of the sections in abutment without liability of damaging parts in the opening of the house. Parts for only one section such as 10, with an extra end 15 may be supplied as a commercial package unit, to which another section 50 may be added subsequently, the parts for which may be sold in an "addition" package. The extra end 15 may be hinged to the open end of the section 10 directly as 55 in Figure 3.

I claim:

A house of the character described, comprising two hingedly connected sections each comprising a front, a back, an end and a 60 gable roof having eaves at the ends and front of the house, the roof stopping flush with the outer face of the back in each section, and the said connection comprising hinges secured to the sections for movement of the 65 sections relatively on an axis at the junction of the connected corners.

In testimony whereof I affix my signature.

FLORENCE ROSENA WALKER.
